UNITED STATES PATENT OFFICE.

ALBERT OTTENHEIMER, OF STUTTGART, GERMANY, ASSIGNOR TO OTTENHEIMER BROTHERS, OF NEW YORK, N. Y.

CORSET.

SPECIFICATION forming part of Letters Patent No. 354,871, dated December 21, 1886.

Application filed June 28, 1886. Serial No. 206,397. (No model.)

To all whom it may concern:

Be it known that I, ALBERT OTTENHEIMER, of Stuttgart, in the Empire of Germany, have invented an Improvement in Corsets, of which 5 the following is a specification.

Corsets have been made with openings at the breasts to accommodate nursing mothers, and fastenings of various kinds have been employed to secure the corset-bosom when closed; but 10 they have been liable to become loose and be very uncomfortable for the wearer.

My invention is made for closing the corset-bosoms with rapidity and for holding them securely, so that they will not become unfastened 15 or the parts misplaced.

In the drawing I have represented the front portions of the corset with one side open and the other closed.

The corset itself is of any desired size or 20 shape, and each bosom portion is made with the two half portions *a* and *b*, with the edges lapping upon each other, the place of separation being vertical, or nearly so, and at *c* is a button and at *d* a button-hole for securing the 25 lapping parts at upper portions of the bosom. If buttons and button-holes alone were used, considerable time would be consumed in opening and properly closing the breast portions of such corset, and the same would be liable to 30 become unbuttoned and no part would yield as the breasts become distended or the reverse. To overcome these difficulties, I introduce an

eyelet or opening in the flap *a*, and pass through the same a cord, *e*, preferably elastic and double, and sew or otherwise fasten the end of such 35 cord to the flap *b*, and this loop of cord is of such a length that when it is drawn up it will reach to and be passed over the button *c*. By this means the middle and lower part of the corset-bosom can be rapidly closed or opened, 40 and the loop of cord prevents the button slipping back through the button-hole, and the cord, being elastic, allows the bosoms of the corset to yield to the distention of the breasts.

I do not claim a corset-bosom having one 45 flap that laps upon the other, nor a button-hole and buttons to secure the same, nor a lacing for the flaps of corset-bosoms.

I claim as my invention—

The combination, with a corset-bosom having 50 two flaps, one lapping upon the other, and a button and button-hole for connecting the flaps at the upper part, of a cord passing through a hole in the outer flap near the middle part of the edge of the same, and connected at its ends 55 to the inner flap, and adapted to pass over the button when the parts have been buttoned together, substantially as set forth.

Signed by me this 10th day of June, 1886.

ALBERT OTTENHEIMER.
